Des. 176,260
Patented Dec. 6, 1955

176,260

COMBINED OXYGEN CABINET AND SUPPORT

John Hughes, Jr., Milwaukee, Wis., assignor to Air Reduction Company, Incorporated, New York, N. Y., a corporation of New York

Application June 6, 1955, Serial No. 36,393

Term of patent 14 years

(Cl. D83—1)

FIG. 1

FIG. 2

FIG. 3

Figure 1 is a perspective view of a combined oxygen cabinet and support, showing the new design;

Figure 2 is a perspective view looking at the right side of the article shown in Figure 1; and

Figure 3 is a perspective view looking at the rear of the article shown in Figure 1.

I claim:

The ornamental design for a combined oxygen cabinet and support, as shown.
